UNITED STATES PATENT OFFICE.

BEN M. HAMLIN, OF CHICAGO, ILLINOIS. ASSIGNOR TO NICHOLAS DIAMOND, OF CHICAGO, ILLINOIS.

WARDROBE TRUNK.

1,418,564.

Specification of Letters Patent. Patented June 6, 1922.

Application filed August 9, 1919. Serial No. 316,355.

To all whom it may concern:

Be it known that I, BEN M. HAMLIN, a citizen of the United States of America, and resident of Chicago, Cook County, Illinois, 5 have invented a certain new and useful Improvement in Wardrobe Trunks, of which the following is a specification.

My invention relates to an improvement in wardrobe trunks, and particularly to 10 means for supporting the follower which operates to hold the garment-hangers and garments supported thereon in proper position.

Various means have been devised for supporting the follower, but I have found that 15 the most efficient results are obtained by supporting this follower above the rods which support the hangers, as by supporting the follower in this manner it bears against the 20 upper edge of the hangers and firmly holds the same in position upon the supporting rods for preventing them from moving during movement of the trunk, while the dust-curtain which is suspended from this follower firmly holds the garments in position.

Other features and objects of my invention relate to certain details hereinafter pointed out which co-operate in increasing the efficiency of the trunk structure.

30 In the accompanying drawings, I have illustrated one specific embodiment of my invention.

Figure 1 is a perspective view of a wardrobe trunk with the sections swung in open 35 position, showing the manner in which the follower is supported in the trunk section.

Fig. 2 is a plan view of the wardrobe section with the cover removed.

Fig. 3 is a front elevation of a portion of 40 the wardrobe section.

Fig. 4 is a detail sectional view.

I have illustrated a trunk comprising a 45 wardrobe section 10, and a tray section 11, hinged together in the usual manner, the wardrobe section being provided with a hinged top or cover 12. Secured to the inside of each side of the wardrobe section 10 and near the upper edge thereof, there is a metallic member 13 provided at its upper 50 edge with a series of grooves or notches 14. Extending inwardly from the lower edge of each of these metallic members there is an angular bracket 15, the inner end of which extends upwardly and supports the rod 16. 55 The inner ends of these rods 16 are suitably supported by the back of the wardrobe sec-

tion 10. Telescoping over these rods 16 are sleeves 17, which sleeves are adapted to be drawn out, as indicated in the left hand portion of Fig. 2, in order to permit of more ready packing of the trunk. The hangers 18 are mounted upon these rods 16 or sleeves 17, as the case may be, and the sleeves 17 are cut away at their forward ends, as indicated at 18', forming a wedge-shaped end which 60 enables this sleeve to be thrust beneath the hooked ends of the hangers resting upon the rods 16. Thus with the sleeve 17 in the outward position shown at the left of Fig. 2, by reason of this wedge-shaped construction of 65 the end of the sleeve, the same can be readily forced into it and beneath the hooked end of the hangers resting upon the rod 16. Mounted in front of the hangers 18 and supported by the upper notched edge of the 70 metallic members 13, there is a suitable follower 19. Extending downwardly from this follower, there is a dust-curtain 20, to the lower edge of which the springs 21 are secured, the opposite ends of these springs being secured to a cross member 22, which at 75 its opposite ends is provided with laterally projecting pins 23 adapted to engage in openings in the racks 24 secured to the inside of the trunk section. With this construction, the follower can be readily adjusted along the upper edge of the metallic members 13 being held in adjusted position by the notches 14 and the operation of the springs 21 which pull downwardly upon the 80 follower. By thus adjusting the follower the same can be made to press firmly against the upper edge of the outside hanger, thus holding the hangers securely in position, which is of the utmost importance in order 85 to insure that the clothing upon the hangers is properly held in position during transit of the trunk. Even a slight movement of the hanger will cause the clothing supported thereon to become stretched or wrinkled, and I have found that by having the follower 90 pressed firmly against the upper edge of the hanger that these hangers can be most efficiently held in place so as to prevent any movement thereof.

Furthermore, by reason of the integral construction of the brackets for holding the hanger rods with the plate for supporting the follower, I am able to provide a very cheap and yet efficient structure. It will be 100 observed further that there are no stiff, 105 crease-forming parts on the upper part of

the compressor positioned to come in contact with the clothing on the hangers, the pressure transmitted to the clothing being entirely from the flexible web or curtain 20, 5 it being obvious that the supporting-rod 19 of the compressor is arranged at a point above the upper end of the garments on the hangers. It will be seen further that an advantage in arranging the supporting-rod 19 10 above the hanger-supports lies in the fact that this supporting-rod 19 may be arranged sufficiently high in the trunk-section to be held in place in the toothed racks by the lid 12 when the same is closed, thereby avoiding 15 the necessity of a special device for holding this rod from being dislodged from the notches and also maintaining the rod at all times in a position where it may be conveniently disconnected from the notched 20 supporting-bars by simply lifting it off the same. A further advantage of mounting the adjustable supporting-rod of the compressor above the hangers is that it enables me to provide an amply strong support for both 25 the supporting rod and the hangers.

While I have illustrated and described one particular embodiment of my invention, it will be understood that I do not wish to be limited to the exact construction shown 30 and described, but that various changes and modifications may be made without departing from the spirit of my invention.

What I claim as my invention is:

1. In a wardrobe trunk, a pair of rods in 35 the upper portion of one section of said trunk, a series of hangers mounted upon said rods, and a follower provided with a supporting bar adjustably supported at its ends by said trunk above said rods and adapted 40 to bear against the upper portion of the hangers mounted on the same.

2. In a wardrobe trunk, metallic members supported near the upper edge of each side of said trunk, a series of notches along the 45 upper edge of said members, a follower whose upper end is adjustably supported in said notches, and angular brackets integrally secured to said members for supporting suitable rods extending below said upper end of the follower, and clothes hangers mounted 50 upon said rods.

3. In a wardrobe trunk, a metallic member supported near the upper edge of each side of said trunk, a series of notches along 55 the upper edge of said members, a follower whose upper end is adjustably supported in said notches, brackets secured to said members for supporting suitable rods extending below said upper end of the follower, and clothes hangers mounted upon said rods.

4. A wardrobe trunk having a compartment, a garment hanger supporter positioned therein, a pair of holding bars at the upper portion of the compartment, one bar on each 60 side of the compartment, said bars having

upwardly-extending projections, a second pair of holding bars below the first pair of bars constructed to adjustably interlock with the ends of the lower bar hereinafter recited, a garment retainer having an upper bar arranged to be seated between the projections on the upper holding bars, a lower bar for the retainer arranged to be adjustably interlocked with the second pair of holding bars, and a flexible connecting member between 75 the upper and lower retainer bars, the upper bar of the garment retainer being above the garment hanger supporter, so that the garment supporting portions of the hangers will be between the upper and lower bars of 80 the retainer, whereby the upper portions of the garments draped on the hangers are compressed by the retainer.

5. In a wardrobe trunk, a hanger section having an upwardly-swinging lid at its upper end, a clothes-hanger-support near the upper end, and a compressor having a rod at its upper end and notched supporting-bars for engagement with the ends of this rod, the rod and notched supporting-bars 90 being arranged above the hanger-supports.

6. In a wardrobe trunk having a hanger section, hanger-supports in said section near the upper end thereof, a compressor having a rod at its upper end, a pair of supporting-bars one at each side of the hanger section and each having an upwardly-extending row of projections with notches between them to receive the ends of said rod and said hanger section being provided with a hinged lid adapted to close down and house the said rod and the upper toothed edges of its supporting bars, for the purpose set forth.

7. In a wardrobe trunk having a hanger section, hanger-supports arranged in the upper end thereof, compressor-supports arranged above the hanger-supports, a compressor having a rod at its upper end adjustably engaging said supports, said compressor consisting of a flexible curtain depending from said rod, and means at the lower end thereof for engaging the side walls of the hanger section.

8. In a wardrobe trunk, a hanger-section, a clothes-hanger-support near the upper end, a supporting-bar at each side of the hanger-section having its upper edge above the hanger-support, said upper edge being provided with a plurality of notches, a compressor having at its upper end laterally-projecting parts which are adapted to rest in said notches to thereby render the compressor adjustable back and forth within the hanger-section, and an upwardly-moving lid on said hanger-section adapted to house the upper edges of said notched bars and to close the notches in the upper edges of the bars.

Signed by me at Chicago, Illinois, this 6th day of August, 1919.

BEN M. HAMLIN.
